TRANSMITTER ARRANGEMENT

Hans Otto Roosenstein, Berlin, Germany, assignor to Telefunken Gesellschaft für Drahtlose Telegraphie m. b. H., Berlin, Germany, a corporation of Germany

Application February 4, 1932, Serial No. 590,904.
In Germany January 30, 1931

3 Claims. (Cl. 179—171)

The object of this invention is an improved circuit arrangement for a wireless transmitter.

It is well known in the art to connect the grid electrode of an oscillator tube by means of a leak-resistance with the cathode, that is, with a point having a negative potential relative to the cathode. According to the present invention the grid leak-resistance of an oscillator tube the plate voltage of which is varied by a modulating device (Heising modulating arrangement) is connected to a point having a positive potential relative to the cathode. Experiments have shown that the operation of such a transmitter circuit is of a different character and far more efficient than the operation of transmitter circuits in which the grid leak-resistance is connected to a point of negative potential or to the cathode itself.

The novel features of my invention have been pointed out with particularity in the claims appended hereto.

The nature of the invention and the mode of operating the same will be better understood by the following detailed description thereof and therefrom when read in connection with the drawings, in which:

Figure 1 shows diagrammatically a circuit arrangement in which the novel features of the present invention have been incorporated; while,

Figure 2 shows a group of curves illustrating graphically the relation between currents in different portions of the circuits of Figure 1.

An embodiment of the circuit in which the invention is incorporated is shown in Figure 1. The figure shows a transmitter circuit in which use is made of a self-controlled oscillator tube 1. The anode 2 of the oscillation generator 1 is regeneratively coupled inductively and capacitively to the grid 7 of tube 4 by the inductances 11 and 12 and capacity 13 to produce sustained oscillations, the frequency of which is determined by the values of said inductances and capacity. The grid anode cathode circuits are completed by way of a radio frequency choking inductance 15 and biasing means to be described more in detail hereinafter. The voltage of the anode 2 of the oscillator tube 1 is varied in accordance with the modulating voltages supplied to the anode 2 in the usual way by means of a modulator 4 having its anode 6 and cathode 5 connected in parallel with the anode 2 and cathode 3 of the oscillator tube 1. A low frequency choke coil 8 is disposed between the common plate voltage supply 16 and anodes 2 and 6. A radio frequency choking inductance 16 pre-

vents radio frequency oscillations from being applied to the output circuit of the modulator tube 4. Modulating potentials may be applied to the input electrode 17 of tube 4 from any source not shown by way of the transformer T. A load circuit, as, for example, an antenna 20, may be coupled by an inductance 19 to an oscillation circuit 11, 13, 12, etc. Difficulties are encountered due to the fact that there are discontinuities in the oscillating diagram of such an arrangement.

Figure 2 shows the oscillating diagram of a transmitter of the type above referred to. In the diagram grid currents I_g have been plotted as a function of the grid voltage (of an oscillator tube). For certain given anode voltages as for instance 300 v., 250 v., 150 v. and 100 v. corresponding values of the electron current flowing to the grid electrode at different values of the grid voltage have been measured and represented by dotted line curves in Fig. 2. In the same way the values of the anode currents are plotted at constant anode voltages as a function of the grid voltage in continuous lines in Fig. 2. As will be seen, when the negative grid voltage exceeds a certain value, the oscillations suddenly break-off. The grid voltages at which this breaking off occurs for the different values of the anode voltage are represented by the dot-dashed lines in the diagram of Fig. 2. These lines separate in the diagram the conditions at which oscillations are built-up from conditions at which oscillations are not obtained.

A grid leak R of the size of 1000 ohms shunted by a capacity C (Fig. 1) was first used. Assuming a grid current of 10 m. a. the potential drop in this resistance causes a negative grid bias of -10 v. of 20 v. at 20 m. a., of 30 v. at 30 m. a. grid current. This relation between the negative biasing potential applied to the grid 7 and the grid current in R is shown by the heavy straight line OP. This line shows the grid voltage which at different grid currents is built-up. Oscillations for grid voltages lying between points Q and P are produced only when more than 220 volts are applied to anode 2. It can be taken from the diagram that at an anode potential of 300 v., a grid current 39 m. a. and a grid potential of -39 v., and an out-put current of 233 m. a. will result; all these values correspond to the point of intersection of the line OP with the grid current curve for plate potential 300 v. For plate voltages below 220 v. the resulting grid potential lie in the region below the breaking-off line and oscillations therefore are not built-

up. At least permanent oscillations are not built-up, and the transmitter may change very rapidly from the not oscillating state to the oscillating state, which even though not always perceptible to the ear in the case of short wave transmitters, results in discontinuities of the modulating characteristics.

If in accordance with this invention a constant positive grid bias supply is used in series 10 with the resistance R, for instance, a source 22, the grid potential resulting from the combined effect of the source 22 and resistance R is represented by the heavy straight line AB, which in this case lies entirely within the region of 15 permanent oscillations of the diagram.

Although due to the modulating device the plate voltage of the oscillator tube may drop practically to zero, the permanent oscillations do not break-off and no discontinuities in the mod- 20 25 30 35 40 45

ulating characteristics can be noticed.

I claim:

1. Transmitting means comprising, a thermionic oscillation generator including a tube having an envelope enclosing an anode, a cathode and a grid electrode, a pair of inductances connected between said anode and grid electrode, a source of potential having its negative terminal connected to said cathode, a resistance connecting the positive terminal of said source to a point 20 25 30 35 40 45

between said first named inductances, a load circuit coupled to one of said first named inductances whereby sustained oscillations are impressed on said load circuit, and means for modulating said oscillations comprising a thermionic modulator tube having its anode coupled by way of a choking inductance to the anode of said oscillator tube and its control electrode energized by modulating potential.

2. Transmitting means comprising, a thermionic oscillation generator including a tube having an envelope including an anode, a cathode and a grid electrode, inductances connected between said anode and grid electrode, a source of potential having its negative terminal connected 20 25 30 35 40 45

to said cathode, a resistance and a capacity in

parallel connecting the positive terminal of said source to a point on said first named inductances, a load circuit coupled to one of said first named inductances, means for energizing the anode of said tube whereby sustained oscillations are impressed on said load circuit, and means for modulating said oscillations comprising a thermionic modulator tube having its anode coupled to the anode of said oscillator tube and its control electrode energized by modulating potentials.

3. In signalling means, a thermionic oscillation generator tube having an anode, a cathode and a grid electrode, an oscillation circuit including an inductance connected between said anode and grid electrode, a circuit connected between a point on said oscillation circuit and the cathode of said tube, a source of potential connected between the cathode of said tube and the anode of said tube, to energize said anode to produce oscillations in said oscillation circuits, means for modulating the oscillations produced including a thermionic tube having its input electrodes coupled to a source of modulating potentials and its output electrodes connected to said first named source and to the anode of said oscillation generator tube, and means for insuring the production of continuous oscillations in said oscillation generator irrespective of decreases of potential on the anode of said oscillation generator resulting from changes in said modulating potentials including a source of direct current potential in series with a resistance shunted by a capacity interposed in said circuit connected between said point on said oscillation circuit and the cathode of said tube, said source of potential having its negative terminal connected to the cathode of said tube and its positive terminal connected to said point on said oscillation circuit, whereby the potential of said control grid is determined in part by potential drop in said resistance due to current flowing in the grid circuit of the oscillation generator and in part by said last named source of direct current potential.
